DESIGN FOR A COMBINED PINCUSHION AND SPOOL HOLDER

Joseph F. Uhlir, Chicago, Ill.

Application April 5, 1939, Serial No. 84,076

Term of patent 14 years

To all whom it may concern:

Be it known that I, Joseph F. Uhlir, a citizen of the United States, residing at Chicago, in the county of Cook and State of Illinois, have invented a new, original, and ornamental Design for a Combined Pincushion and Spool Holder, of which the following is a specification, reference being had to the accompanying drawing, forming part thereof.

I claim:

The ornamental design for a combined pincushion and spool holder, as shown.

JOSEPH F. UHLIR.
